UNITED STATES PATENT OFFICE.

PHILEMON O. DICKINSON, OF NEWARK, NEW JERSEY.

DESIGN FOR A BACK FOR BRUSHES, &c.

SPECIFICATION forming part of Design No. 24,920, dated November 26, 1895.

Application filed October 24, 1895. Serial No. 566,787. Term of patent 3½ years.

To all whom it may concern:

Be it known that I, PHILEMON O. DICKINSON, a citizen of the United States, residing at Newark, in the county of Essex and State of New Jersey, have invented and produced a new and original Design for the Backs and Handles of Brushes, Mirrors, and other Articles, of which the following is a description, reference being had to the accompanying drawing, which illustrates the design.

The drawing shows a representation of the back of a brush and handle thereof ornamented with my design.

The outline shape of the back is oval. The outline shape of the handle is also oval, but of smaller size. Running around the edge of

the back and handle and slightly within the profile line is the rococo border A. At the top of the back of the brush is the plain disk B, and at the middle and lower end of the back are the disks C and D, the spaces B, C, and D being left plain. The handle similarly bears open spaces E and F.

The essential features of the design are those above set forth. 25

What is claimed as new is—

The design for the back and handle of a brush, substantially as shown and set forth.

PHILEMON O. DICKINSON.
